[57] **CLAIM**

The ornamental design for a sink, as shown and described.

DESCRIPTION

FIG. 1 is a perspective view taken from the top, right side and rear of a sink embodying my new design;

FIG. 2 is a top view thereof;

FIG. 3 is a cross-sectional view taken on line 3—3 of FIG. 2;

FIG. 4 is a perspective view taken from the top, right side and rear of a second embodiment of my new design, of which the top view is essentially the same as FIG. 2 albeit the sink is less deep; and,

FIG. 5 is a cross-sectional view taken on line 5—5 of FIG. 4.

In the preferred embodiment, the bottom is plain and unornamented except for the drain opening, which is located as shown in the drawings.
